ART OF HYDROCARBON OIL CONVERSION

Carbon P. Dubbs, Wilmette, Ill., assignor, by
mesne assignments, to Universal Oil Products
Company, Chicago, Ill., a corporation of Dela-
ware

Application March 7, 1927, Serial No. 173,268
Renewed March 24, 1934

8 Claims. (Cl. 196—58)

The present improvements relate more particularly to a process and apparatus primarily designed to effect conversion of hydrocarbon oils of high boiling point range into hydrocarbons of 5 lower boiling point range suitable for commercial use.

The invention in its broad aspects embraces a process and apparatus for simultaneously topping crude oil and subjecting the topped crude to 10 cracking conditions of temperature and superatmospheric pressure.

The invention is characterized by its adaptability, flexibility, and economy. The arrangement is such that the process can be operated 15 to produce maximum yields of condensed overhead products, such as gasoline and the like, with a minimum production of non-vaporous residue, or the process may be operated to produce a minimum yield of light overhead products and a maximum yield of non-vaporous products, including 20 all of the range between these two alternatives.

The invention is also characterized by the fact that the process may be so operated as to efficiently 25 work on any type of charging stock included in a range from a low gravity heavy viscous residue up to and including a kerosene-like charging stock having a Baume gravity of 40°, more or less.

As a feature of the invention, the charging stock is subjected to a preheating temperature by 30 being caused to pass through a closed circuit, thus causing vaporization of the real light constituents of said charging stock. These vapors are permitted to be released, and separately condensed and collected. That portion of the charging stock which does not vaporize due to this 35 preheating is then subjected to cracking conditions of temperature and superatmospheric pressure, sure to cause substantial conversion and separation of vapors. The utility of the invention as 40 well as many other objects and advantages will be more apparent from the following description.

The single figure in the drawing designates a 45 diagrammatic flow chart of the invention.

Referring more in detail to the drawing, 1 designates a crude oil storage receptacle from 50 which oil is passed through the line 2 in which may be interposed the pump 3 and meter 4 to the coil 5 mounted in heat exchanger 6 connected by branches 1 controlled by valves 8. Or this 55 preheater may be by-passed by closing valves 8 and opening the valve 9 in the line 10. The charging stock may be then passed through the closed coil 11 mounted in the heat exchanger 12

through the branches 13 controlled by valves 14, or by closing the valves 14 the coil 11 may be bypassed, and the oil passed through the line 15 controlled by valve 16 communicating with line 17. The line 17 may communicate with the 5 closed coil 18 mounted in the upper portion of a dephlegmator 19 by means of the branches 20 controlled by valves 21. Or the closed coil 18 may be by-passed by passing the oil through the by-pass line 22 which is controlled by valve 23. The oil in either event passes into the line 24 10 and into the water separator 25.

The desirability of subjecting the crude oil to the various preheating steps will be based upon 15 the conditions of operation, gravity and characteristics of charging stock and products desired. Where the crude oil contains water, it will be advisable to subject it to one or more of the preheating stages illustrated, so that the temperature of the crude by the time it reaches the 20 water separator will be around, say 250° to 400° F. Water which may separate in the water separator 25 may be withdrawn through the line 26 controlled by valve 27. The crude passes out through the line 28 and may pass through the closed coil 25 29 mounted in preheater 30 through the branches 31 controlled by valves 32, or the crude may be by-passed by opening valve 33 in line 34. The crude may then pass through the line 35 controlled by valve 36 being introduced into a vapor 30 separator 37. This vapor separator 37 in the present invention may preferably take the form of a fractionating column provided with the usual baffles. The vapors which have formed due to the preheating steps, separate in the vapor separator, 35 and those which remain uncondensed after passage through the vapor separator pass out through the vapor outlet line 38 through heat exchanger 6, condenser 39, collecting as a liquid in the receiver 40. This receiver 40 may be equipped with 40 the usual uncondensable gas relief pipe 41 controlled by valve 42, and with a liquid draw off pipe 43 controlled by valve 44. For the purpose of assisting in the fractionation of the vapors separating in the vapor separator 37, a controlled 45 quantity of the liquid collected in the receiver may be returned through the line 45 in which may be interposed a pump 46 and valve 47, the line 45 discharging into the top of the vapor separator 37.

From the foregoing it will be apparent that I have utilized the waste heat from the cracking system for the purpose of vaporizing the lighter fractions contained in the crude oil, which lighter fractions are vaporized, separated, fractionated, 55

and those remaining uncondensed collected separately in the receiver 40.

The topped crude collecting in the lower portion of the vapor separator 37 is withdrawn 5 through the line 48, in which may be interposed a hot oil pump 49 and valve 50, being forced through the heating tube 51 mounted in the furnace 52 where it is raised to a conversion temperature of, say 750° to 950° F. The heated oil 10 from the heating tube 51 passes out through transfer line 53 in which may be interposed a valve 54 discharging into a reaction chamber 55 where vapor separation is permitted to take place. The vapors separated in reaction chamber 55 15 may pass out through vapor outlet pipe 56, in which may be interposed a valve 57, being introduced into a compartment 58 in the dephlegmator 19, defined by partitions 59 and 60. These vapors pass upwardly through the open ended uprights 20 61 discharging into the interior of the dephlegmator 19. The dephlegmator 19 is provided with the usual baffles, pans, or the like. Reflux condensate preferably collects, as indicated, in a pool 62 surrounding the uprights 61. The arrangement 25 is such that the heat of the vapors passing upwardly through the uprights 61 strips the reflux condensate in the pool 62 of the light fractions which may be entrained therein, due to the reboiling action which takes place. The vapors 30 remaining uncondensed after passage through the dephlegmator 19 pass out through the vapor outlet pipe 63 controlled by valve 64, through heat exchanger 12, condenser 65, collecting in receiver 66 as liquid condensate. The receiver 66 is provided with the usual gas relief pipe 67 controlled 35 by valve 68, and with the liquid draw off pipe 69 controlled by valve 70.

Regulated portions of the distillate collecting 40 in the receiver 66 may be returned through the line 71 in which may be interposed a pump 72 and valve 73, to the upper portion of the dephlegmator 19.

In one method of operation, the valve 57 in the vapor transfer line 56 from reaction chamber 55 45 to the dephlegmator 19 is a pressure reducing valve whereby the pressure maintained on the heating tube 51 and chamber 55 is reduced or released altogether.

The non-vaporous residue may be withdrawn 50 from the reaction chamber 55 through any of the draw off lines 74 controlled by valve 75 discharging into the common header 76. To assist in the withdrawal of this residue and to prevent the accumulation of substantial quantities of coke or 55 coke-like material in the chamber 55, an agitator designated diagrammatically at 77 and which may be operated by the motor 78 may be provided. All or any regulated portion of the residue passing through the residue draw off line 76 may be 60 diverted into the line 79 controlled by valve 80, which line 79 communicates with the heat exchanger 30, from which it discharges into the line 81, further cooling the residue by means of the instrumentality 82, said residue being finally collected in the residue storage receptacle 83.

All or regulated portions of the residue passing through the line 76 may be diverted through the line 84 controlled by valve 85 into the interior of a flash chamber 86. In the drawing 70 the dephlegmator 19 and flash chamber 86 are illustrated as one instrumentality. It is obvious that these elements may be separate instrumentalities within the contemplation of the invention.

75 As a feature of the invention, the pressure

maintained on the residue passing through the line 84 is materially reduced or released altogether, the valve 85 acting as a pressure reducing valve, whereby substantial separation of vapors due to latent heat takes place in the flash chamber 86. These vapors may be removed from the chamber 86 through the vapor line 87 controlled by valve 88, being introduced to the interior of the dephlegmator 19 where they combine with the vapors introduced from the transfer line 56 directly from the reaction chamber 55.

As another feature of the present invention, in order to control the gravity and quality of the residue produced, which is particularly important when the residue is to be sold commercially 15 as a fuel oil, regulated portions of the crude oil may be diverted through the line 89 controlled by valve 90 into the line 91 through line 92 controlled by valve 93 into the residue draw off header 76. It is to be noted that the invention 20 contemplates that the crude oil used for the purpose of mixing with the residue in the header 76 may or may not be previously preheated, depending entirely on conditions of operation. However, to permit preheated crude oil to be 25 diverted, I provide a branch 94 controlled by valve 95 connecting respectively the pipes 35 and 91. In case it may be desirable to slightly cool the preheated crude oil before introducing same to the residue draw off header 76, the valve 96 in 30 the branch 97 leading to cooling coil 98 may be opened. After passing through the cooling coil 98 the crude may be introduced through the branch 92. If it is desired to introduce regulated portions of the topped crude it may be 35 done by diverting regulated portions through the pipe 97 either directly through the branch 99 controlled by valve 100 or through cooling coil 98.

The residue formed in the flash chamber 86 may be withdrawn through the upper line 101, 40 and by opening valve 102 may be discharged into the residue draw off line 79 and passed to storage 83. Or the residue may be diverted from the lower line 101 into the line 103 controlled by valve 104, cooled in cooling coil 105 and collected in 45 any suitable receptacle.

As another feature of the present invention, it may be desirable in some operations to produce a maximum yield of overhead products, with little or no liquid residue. In other words, 50 it may be desirable to carry out what is termed a non-residuum process in which little or no substantial liquid residue is produced, the object of the process being to produce mainly a condensed overhead product and a substantial non-flowing coke-like product. With such an operation it may be further advisable to subject a portion of the liquid residue withdrawn through the header 76 to conditions of flashing in the chamber 86 in order to maintain the desired capacity. 60 In such event the residue withdrawn from the flash chamber 86 may be diverted through either or both of the lines 106 controlled by valves 107 merging in a common return line 108, in which may be interposed a pump 109, returning said 65 residue either to the transfer line 53 through the proper manipulation of the valve 110 in the line 111 or directly into the reaction chamber 55 by proper manipulation of the valve 112 in the branch 113.

In addition to the methods of controlling the quantity or gravity of the residue as described, a controlled quantity of the raw oil may be diverted through the line 114, passed through closed coil 115 positioned in the vapor space of 75

the flash chamber 86 and controlled by the valves 116. By regulating the amount and temperature of the oil passing through the closed coil 115, the condensation or cooling of the vapors released in flash chamber 86 may be definitely controlled. It will be obvious that the condensation of the vapors will directly control the quality and gravity of the non-vaporous residue produced.

10 Reflux from the pool 62 which has been stripped of all the light fractions may be withdrawn through the line 117 and mixed with the topped crude to be returned through the line 48 to the cracking zone.

15 The temperature and pressure conditions to be maintained on different parts of the plant will depend entirely upon the operating conditions, the type of charging stock used, and the products desired. It may be stated, however, that in the 20 preferred form of the invention, the heating tube 51 and reaction chamber 55 are preferably maintained under a higher pressure than the dephlegmator 19 and flash chamber 86. For instance, the pressure in the heating tube 51 and reaction 25 chamber 55 may be from 100 to 3000 pounds, more or less, while the pressure on the balance of the system may be materially reduced or even released, only carrying such a pressure as is necessary to overcome frictional resistance.

30 From the foregoing it will be apparent that the invention has been carefully worked out to provide a method of hydrocarbon oil conversion comprising among other features, wide flexibility in operating conditions, the use of charging stocks 35 of wide ranges and characteristics, the production of maximum quantities of desired products, coupled with the ability to be so manipulated as to be completely reversed and produce maximum yields of entirely different products.

40 I claim as my invention:

1. A process for converting hydrocarbons into lighter hydrocarbons comprising subjecting the heavy hydrocarbons to cracking conditions of temperature and pressure in a heating zone, separating the vaporous from the unvaporized liquid products, passing the unvaporized liquid products to a distillation zone, materially lowering the pressure on the unvaporized liquid products delivered to said distillation zone to effect distillation 45 of the unvaporized liquid products in said distillation zone by the contained heat thereof, passing said vaporous products to a cooling zone wherein insufficiently cracked fractions are condensed, also passing vapors released from the unvaporized liquid products in said contained heat distillation zone to said cooling zone, controlling the degree of cooling in said cooling zone and the degree of distillation in said contained heat distillation zone by circulating heavy hydrocarbons 50 being supplied to the process through said cooling zone and through said distillation zone, and subsequently supplying the heavy hydrocarbons so circulated to said heating zone.

2. A process for cracking hydrocarbon oil, 65 which consists in subjecting the oil to cracking conditions of temperature and pressure in a heating zone, separating the primary vapors from the unvaporized residue, effecting distillation of said residue by contained heat thereof under reduced 70 pressure in a flash distilling zone, subjecting said primary vapors to a cooling treatment to condense insufficiently converted fractions thereof, controlling the degree of said contained heat distillation, and the degree of cooling of said primary vapors by circulating heavy hydrocarbons 75

being supplied to the process in heat interchange relationship with the primary vapors and through said flash distilling zone, subsequently separating from said heavy hydrocarbons those constituents vaporizable at the temperature acquired by heat 5 interchange, collecting such constituents independently of other products of the process, and supplying the unvaporized heavy hydrocarbons to said heating zone.

3. An oil cracking process which comprises 10 heating the oil under pressure to a conversion temperature in a heating zone, passing the heated oil to a conversion zone wherein a separation of vapors and unvaporized oil is effected, passing the vapors to a dephlegmating zone, removing said 15 unvaporized oil from the conversion zone and reducing the pressure thereon to effect a distillation thereof, cooling the vapors evolved by such reduction in pressure by passing in heat exchange relation therewith charging stock for the process, 20 subsequently introducing said vapors to said dephlegmating zone to commingle therein with the first mentioned vapors, cooling the vapors in said dephlegmating zone by heat exchange with charging stock for the process, stripping reflux condensate of entrained light fractions by indirect heat exchange with the first mentioned vapors separated in said conversion zone, passing said charging stock and reflux condensate to said 25 heating zone, and condensing the uncondensed 30 vapors.

4. A cracking process which comprises heating hydrocarbon oil to cracking temperature under pressure while flowing in a restricted stream through a heating zone, discharging the heated oil into an enlarged reaction zone maintained under cracking conditions of temperature and pressure, removing vapors and unvaporized oil from the reaction zone and flash distilling the latter 40 in a flashing zone by pressure reduction, introducing resultant flashed vapors and the vapors removed from the reaction zone into a dephlegmating zone and subjecting the same therein to common fractionation to condense insufficiently cracked fractions thereof, introducing fresh 45 charging oil for the process into heat exchange relation with vapors in the dephlegmating zone, passing another portion of the charging oil in indirect heat exchange relation with vapors in the 50 flashing zone, and subsequently supplying components of said portions of the charging oil heavier than gasoline to said heating zone.

5. A cracking process which comprises heating hydrocarbon oil to cracking temperature under 55 pressure while flowing in a restricted stream through a heating zone, discharging the heated oil into an enlarged reaction zone maintained under cracking conditions of temperature and pressure, removing vapors and unvaporized oil 60 from the reaction zone and flash distilling the latter in a flashing zone by pressure reduction, introducing resultant flashed vapors and the vapors removed from the reactions zone into a dephlegmating zone and subjecting the same there- 65 in to common fractionation to condense insufficiently cracked fractions thereof, passing crude oil containing desirable light fractions in indirect heat exchange relation with hydrocarbon constituents in the flashing zone thereby supply- 70 ing heat to the crude oil and controlling the degree of distillation in the flashing zone, vaporizing said light fractions from the crude oil and condensing and collecting the same, and supply- 75 ing heavier portions of the crude oil in admix-

ture with reflux condensate from the dephlegmating zone to said heating zone.

6. A cracking process which comprises heating hydrocarbon oil to cracking temperature under pressure while flowing in a restricted stream through a heating zone, discharging the heated oil into an enlarged reaction zone maintained under cracking conditions of temperature and pressure, removing vapors and unvaporized oil from the reaction zone and flash distilling the latter in a flashing zone by pressure reduction, introducing resultant flashed vapors and the vapors removed from the reaction zone into a dephlegmating zone and subjecting the same therein to common fractionation to form a composite reflux condensate of heavier fractions of the flashed vapors and insufficiently cracked fractions of the first-named vapors, passing crude oil in indirect heat exchange relation with the vapors undergoing common fractionation in the dephlegmating zone and heating the same to distillation temperature, introducing the heated crude oil into a topping and fractionating zone apart from said dephlegmating zone and topping and fractionating the same therein independently of the vapors in the dephlegmating zone to separate lighter fractions thereof as vapor, finally condensing and collecting these vaporized lighter fractions of the crude, combining heavier fractions of the crude with composite reflux condensate from the dephlegmating zone and supplying the resultant mixture to the heating zone, and

finally condensing and collecting the vapors uncondensed in the dephlegmating zone independently of said vaporized lighter fractions of the crude.

7. A conversion process which comprises subjecting hydrocarbon oil to cracking conditions of temperature and pressure in a cracking zone, removing vapors and unvaporized oil from the cracking zone, simultaneously topping and fractionating crude oil in a topping and fractionating zone to separate light fractions from heavier fractions thereof recovering the light fractions, combining a portion of the heavier fractions of the crude with said unvaporized oil and distilling the resultant mixture in a flashing zone maintained under lower pressure than the cracking zone, fractionating vapors from the flashing zone independently of the crude oil in said topping and fractionating zone and in admixture with the first-named vapors in a dephlegmating zone apart from said topping and fractionating zone to form a composite reflux condensate, supplying such reflux condensate together with another portion of the heavier fractions of the crude to the cracking zone, and finally condensing the fractionated vapors.

8. The process as defined in claim 4 further characterized in that the first-named charging oil is passed in indirect heat exchange relation with vapors in the dephlegmating zone.

CARBON P. DUBBS.
